UNITED STATES PATENT OFFICE.

LEWIS R. KELLER, OF NEW YORK, N. Y.

DESIGN FOR A COMBINATION CALENDAR AND KITCHEN-MEMORANDUM CARD.

Application filed December 19, 1925. Serial No. 15,789. Term of patent 7 years.

To all whom it may concern:

Be it known that I, LEWIS R. KELLER, a citizen of the United States, and a resident of the city of New York, borough of Manhattan, in the county and State of New York, United States of America, have invented a new, original, and ornamental Design for a Combination Calendar and Kitchen-Memorandum Card, of which the following is a specification, reference being had to the accompanying drawing, forming part hereof.

The drawing is a perspective view of a combination calendar and kitchen memorandum card embodying the design.

I claim:

The ornamental design for a combination calendar and kitchen memorandum card as shown.

LEWIS R. KELLER.
